ATTORNEY

UNITED STATES PATENT OFFICE.

FRITZ REICHMANN, OF ALBANY, NEW YORK.

TOOTH-BRUSH.

1,090,126.

Specification of Letters Patent. Patented Mar. 10, 1914.

Application filed July 15 1912. Serial No. 709,350.

To all whom it may concern:

Be it known that I, FRITZ REICHMANN, a citizen of the United States, residing at Albany, county of Albany, and State of New York, have invented certain new and useful Improvements in Tooth-Brushes, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view partly in side elevation and partly in vertical, longitudinal section of a tooth-brush embodying my invention. Fig. 2 is a view in side elevation of one of the brush-units detached. Fig. 3 is a view in side elevation of a tooth-brush embodying my invention showing the brush-units connected together by intermeshing gears. Fig. 4 is a top plan view of the same.

The principal object of the invention is to cause in the use of a tooth-brush a revolvable action of the several bristles about an axis extending longitudinally of the respective bristles.

Other objects will appear in connection with the following description.

Referring to Figs. 1 and 2, 1 is the handle of the tooth-brush upon which are separately rotatively mounted a plurality of brush-units, 2, arranged longitudinally along the under side of the handle. In the preferred form of my invention these brush-units are made separable and they may be removably and rotatively mounted upon the handle in any known manner, such that the bristles will project substantially at right angles to the under side of the handle.

As shown, each brush-unit, 2, comprises a tuft or knot of bristles, 3, mounted in a head, 4, adapted to form the male member of a snap-fastener and adapted to be sprung into, and to be yieldingly held by, a socket, 5, forming the female member of the snap-fastener. The socket, 5, is shown fixed upon the lower end of a spindle, 6, which is rotatively mounted in the head portion of the handle, 1.

The several spindles, 6, extend perpendicularly through the handle from the under

to the upper side thereof and the brush-units are thus rotatively mounted upon the handle with their bristles projecting perpendicularly from the under side of the handle; and the brush-units are adapted to separately rotate, each about an axis perpendicular to the handle, so that a revolvable movement is imparted to the several bristles about an axis extending longitudinally of the respective bristles.

For certain purposes of the invention the tufts or knots of bristles may be of any desired form.

To facilitate automatic rotation of the respective brush-units in use, I prefer to provide the several tufts or knots with an inclined or beveled face or end, 7, by having the bristles of gradually increasing length from one side to the other of the tuft or knot as shown. By thus beveling the ends of the tufts or knots, their longer sides will tend to engage the teeth with greater force than the shorter sides, thus tending to rotate the several brush-units as the brush is passed by a longitudinal movement along the teeth.

Worn brush-units can be pulled out of the respective sockets, 5, and new ones sprung thereinto when desired.

As shown in Figs. 3 and 4, the brush-units are connected together by intermeshing gears, 8, whereby a rotative movement of one of the units is transmitted to each of the other units.

What I claim as new and desire to secure by Letters Patent is—

1. A tooth-brush comprising a handle and a plurality of knots of bristles rotatively mounted upon the side of the handle upon axes extending longitudinally of the respective bristles and arranged in a row parallel with the handle, the several knots being beveled whereby they are adapted for self-rotation.

2. A tooth-brush having a handle and a knot of bristles projecting laterally from the handle and rotatively mounted thereupon on an axis perpendicular to the handle, said knot having its outer end beveled.

3. In a tooth-brush and in combination, a handle; a plurality of brush-unit-holders rotatively mounted upon the handle; and brush-units removably mounted upon the respective brush-unit-holders.

4. In a tooth-brush and in combination, a handle; a plurality of brush-units rotatively mounted upon the handle on axes per-

pendicular thereto; and gear connections between the respective brush-units, the several brush-units having a knot of bristles projecting perpendicularly from the side of the handle, the outer end of said knot being beveled.

5. In a tooth-brush and in combination, a handle; a plurality of brush-unit-holders rotatively mounted upon the handle and each 10 having a snap-member, and brush-units each

having a snap-member whereby it is removably mounted in connection with the snap-member on one of said brush-unit-holders.

In testimony whereof, I have hereunto set my hand this 9 day of July, 1912.

FRITZ REICHMANN.
